LASTING MACHINE

Harold Lane and Horace Harry Dyson, Leicester, England, assignors to United Shoe Machinery Corporation, Paterson, N. J., a corporation of New Jersey

Application October 13, 1934, Serial No. 748,160
In Great Britain November 29, 1933

12 Claims. (Cl. 12—4)

This invention relates to lasting machines and more particularly to machines for lasting the heel ends of shoes. The invention is herein illustrated as applied to a machine of the type disclosed in United States Letters Patent No. 1,949,539, granted on March 6, 1934 upon an application of Joseph Gouldbourn, Fred Ricks and William T. B. Roberts, but it is to be understood that it is not limited to machines of that particular type.

Heel-end-lasting machines commonly include heel-lasting wipers for wiping the marginal portion of the upper inwardly over an insole or other shoe bottom part on the last and a heel-end-clamping device or heel band for clamping the upper materials about the heel end of the last prior to the operation of the wipers on the upper, the shoe and last being mounted on a work support or jack movable to carry them into position to be embraced at the heel end by the heel band. It has been found that if the heel-end-lasting operation is performed prior to the customary side-lasting operation, or under some conditions even if the lasting of the heel end follows the lasting of the sides, the heel band and wipers may tend to displace portions of the upper in such manner as to produce immediately in front of the heel seat undesirable wrinkles in the upper materials. To avoid this result it is sometimes the practice to drive tacks to fasten the opposite side margins of the upper materials in proper positions near the forward end of the heel seat prior to the heel-end-lasting operation. In order to eliminate the necessity for this manual operation, it has been proposed heretofore to provide heel-end-lasting machines with special means for controlling the upper forwardly of its heel-end portion, as disclosed, for example, in an application of William T. B. Roberts, Serial No. 712,914, filed on February 26, 1934.

It is an object of the present invention to provide improved means for controlling the upper materials forwardly of the heel-end portion of the shoe for the purpose above described. To this end, the construction shown comprises novel means whereby the upper materials are clamped against the sides of the last and the edge of the insole or other shoe bottom part on the last in locations just in front of the heel-end portion of the shoe after the shoe support has been moved to carry the heel end of the shoe within the heel band but before any substantial clamping action of the heel band against the opposite sides of the shoe, such means being so constructed that portions thereof adjacent to the shoe are located

wholly below the plane of the wiping faces of the heel-end wipers, so as to be entirely out of the way of the wipers, and yet are in positions to hold the upper effectively in locations immediately adjacent to the plane of operation of the wipers to insure against any wrinkling of the upper at the edge of the shoe bottom forwardly of the heel seat by the action of the wipers. As illustrated, and in accordance with a further feature of the invention, such clamping means comprises clamp members which are combined with other members arranged to clamp and control the shoe and last in locations spaced substantial distances heightwise of the last from the edge of the shoe bottom, the different members at each side of the shoe being relatively movable widthwise of the shoe and connected together so that their pressures on the shoe are substantially equalized. In operating on comparatively small shoes the use of the members located at distances from the shoe bottom may be unnecessary and even undesirable, and accordingly the construction shown further comprises means whereby these members may, if desired, be rendered inoperative.

A further object of the invention is to provide upper-controlling means such as to facilitate the use as well as improve the operation of a heel-end-lasting machine on uppers which, at the time of presentation of the work to the machine, are loose on the lasts. The upper of a Veldtschoen shoe, for example, is commonly in this condition, so that it is necessary for the operator to hold the heel end of the upper in correct relation to the last until the heel band or the wipers begin to operate on the shoe after the starting of the power operation of the machine. Since the space around the heel band and the wipers in machines at present in general use is restricted, it is somewhat difficult for the operator to do this. The present invention accordingly provides a construction such that the above-mentioned upper-controlling members, although operated by power to press them firmly against the upper after the starting of the power operation of the machine, are moved into upper-controlling positions by the operator prior to the starting of the machine, so that he need no longer hold the upper as above described. A further desirable characteristic of the construction shown is that the upper-controlling members thus applied have a forward tightening effect on the upper about the heel end of the last after the starting of the machine, as more particularly hereinafter explained.

The above and other features of the invention, including various novel details of construction

and combinations of parts, will now be more particularly described by reference to the accompanying drawing and pointed out in the claims.

In the drawing,

5 Fig. 1 is a plan view of a portion of a heel-end-lasting machine in which the invention is embodied;

10 Fig. 2 is a view in front elevation of a portion of the structure shown in Fig. 1, with the parts 15 shown in the positions which they occupy when clamping a shoe, a portion of the structure being shown in section;

15 Fig. 3 is a view in right-hand side elevation of a portion of the structure shown in Figs. 1 and 2, with parts in section; and

Fig. 4 shows in right-hand side elevation means provided for controlling a portion of the structure shown in Fig. 1.

Since the invention is herein illustrated as embodied in means intended to form part of a machine of the same general type as disclosed in the above-mentioned Letters Patent No. 1,949,539, only such parts of the machine as it is necessary to refer to for an understanding of the invention 20 are shown and will be particularly described. The machine is provided with a work support or jack 1, shown in broken lines in Fig. 3; having on its upper end a spindle 3 for engaging each last in its spindle hole. As common in machines of the illustrated type, the jack is supported at its 25 lower end, by means not herein shown, for forward and rearward swinging movements, as indicated by the arrows A, so as to receive the shoe in an idle forwardly inclined position and 30 to carry the shoe rearwardly to present it to the lasting mechanism. This mechanism comprises the usual heel band 5 for clamping the upper about the heel end of the last and wipers 6, shown in dotted lines in Fig. 3, for wiping the 35 marginal portion of the upper inwardly over an insole or other shoe bottom part on the last. The jack is swung rearwardly by the operator to carry the heel end of the shoe to a position within the heel band and then, through mechanism with 40 which machines of the illustrated type are commonly provided, is lifted by a treadle 7 (Fig. 4) until the heel end of the insole or other shoe bottom part on the last comes into contact with 45 holdown members 9 which serve to position the 50 work at the correct height for the heel-end-lasting operation.

The machine is further provided with a pair of bell-crank levers 11 similar to the bell-crank levers 198 shown in the above-mentioned Letters Patent No. 1,949,539. In the construction herein shown each of these bell-crank levers carries a block 13 adjustably secured to its forwardly extending arm by a bolt 15 integral with the block. Each of these blocks has formed on 55 it an inwardly extending cylindrical portion 17 (Fig. 2) in which is housed a spring 19, this spring surrounding and urging outwardly (i. e. toward the right as viewed in Fig. 2) a stud 21 the outer end of which has a head thereon engaged by the 60 spring and the inner end of which carries a cross pin 23 bearing against a second block 25. By means of a tongue-and-groove connection between the blocks 13 and 25 the latter is normally positioned in fixed relation to the former. The 65 blocks 25 have clamped therein the lower ends of upwardly extending arms 27 which normally project in front of the forward ends of the heel band 5. To permit access to the heel band each block 25 may be pulled inwardly against the 70 resistance of the spring 19 to break its tongue-and-

groove connection with the block 13 so that the arm 27 may be swung forwardly and downwardly about the cylindrical portion 17.

Each of the upwardly extending arms 27 has 5 formed in it, one above the other, two slideways extending laterally of the machine, in the upper one of which is mounted a slide 29 provided on its inner end with a rectangular rubber pad 31 for engaging the shoe upper, this pad and the slide 29 being so positioned that when a shoe is 10 pressed against the holdown members 9 the pad, when operated, will press the upper materials against the side of the last and against the edge of the insole or other shoe bottom part on the last, the pad being positioned just below the plane 15 of operation of the wipers 6 and arranged to engage the upper immediately in front of the heel-end portion of the shoe and of the heel band 5. The arms 27 are preferably so adjusted in the 20 blocks 25 that when the forwardly extending arms of the bell-crank levers 11 are swung inwardly toward each other the portions of the pads which are farthest from the heel-end face of the last first engage the upper, and thereafter as the 25 arms are further operated to press the pads firmly against the upper the area of contact between the pads and the upper increases progressively toward the heel-end face of the last until the whole of the shoe-engaging faces of the pads are 30 in firm contact with the upper. In this manner the pads 10 tend to work the portions of the upper which they engage somewhat rearwardly, which assists in counteracting such tendency as the forward ends of the heel wipers may have 35 to crowd the upper forwardly.

The lower slideway in each of the arms 27 has 40 mounted therein a second slide 33 which lies in the same vertical plane as the slide 29 and carries at its inner end a last-supporting member or pad 35. The pads 35 thus serve to clamp the opposite sides of the shoe and last in locations just 45 forwardly of the heel band and where the sides of the last slope inwardly toward its top portion, and thereby assist in preventing tipping movement of the last lengthwise or laterally under the pressure of the heel band and the wipers. The slides 29 and 33 are coupled together by a lever 37 pivoted midway between its opposite ends on a stud 39 fixed in the arm 27, the ends of this lever 50 extending into notches formed in the slides 29 and 33. Accordingly, if either of the members 31 engages the shoe before the member 35 associated therewith, the lever 37 causes the member 35 to be forced rapidly inward into operative position, after which the pressures of the members 31 and 35 on the shoe are substantially equalized through the lever. The lever, of course, will 55 act in a similar manner if the member 35 should engage the work before the member 31.

When operating on comparatively small shoes 60 the use of the supporting members 35 may be not only unnecessary, but undesirable. Means, therefore, is provided whereby the lower slides 33 may be locked in inoperative positions with the members 35 spaced well away from the work. 65 For this purpose each of the arms 27 carries, just beneath the inner end portion of the upper slide 29, a pivoted hook-shaped distance piece 41 which is normally in an inoperative position but can be swung upwardly by a finger piece 43 70 thereon so as to lie in a space between the inner side of the arm 27 and a shoulder 44 on the slide 29 after the member 31 has been pushed inwardly and the member 35 outwardly by the operator. The distance piece 41 will then prevent inward 75

movement of the slide 33 in response to pressure of the shoe on the member 31, so that the member 35 will remain inoperative.

The bell-crank levers 11 are operated to swing their forwardly extending arms inwardly toward the shoe in the initial portion of the power operation of the machine by mechanism similar to that disclosed in the previously mentioned Letters Patent No. 1,949,539. For this purpose the bell-crank levers are connected by rearwardly extending links 45 (Fig. 1) to the opposite ends of an equalizing lever 47 which is pivoted substantially midway of its length to the central portion of a horizontal transversely extending lever arm 49 mounted at its left-hand end on a vertical pivot (not shown). Swiveled in the forked right-hand end of the arm 49 is a pin 50 through which extends a horizontal rod 51 connected at its rear end to operating means not herein shown but fully disclosed in the above-mentioned Letters Patent. On its forward end the rod 51 is provided with nuts 53, and between these nuts and a sleeve 54 in engagement with the pin 50 is a spring 55 through which rearward swinging movement is imparted yieldingly to the arm 49 by rearward movement of the rod 51 to operate the bell-crank levers 11 and thereby force the pads 31 and the members 35 against the shoe.

We have found that, particularly in operating on Veldtschoen shoes, the presentation of the work to the machine is facilitated and improved results are obtained in operating on the upper if the pads 31 are made to engage the shoe prior to the starting of the power operation of the machine. For this purpose the machine herein shown is accordingly further provided with a bell-crank lever 57 (Fig. 4) having an upwardly extending arm arranged to engage the arm 49 on the front side of the latter and having also a short horizontal arm connected by a rod 59 to one arm of a double lever 61 the other arm of which lies beneath the jack-operating treadle 7. A space, however, is provided between this arm of the lever 61 and the treadle, so that the bell-crank lever 57 will be operated only in the final portion of the downward movement of the treadle. There is also mounted on the rod 51 between the pin 50 and an adjustable hand wheel 63 on the rod a comparatively light compression spring 65. Accordingly the arm 49 is swung relatively to the rod 51 against the resistance of the spring 65 by operation of the bell-crank lever 57 in the final portion of the downward movement of the treadle 7, so that the pads 31 and the members 35 are carried into engagement with the shoe just as the latter is forced against the holdown members 9 by the treadle. The loose upper of a Veldtschoen shoe is therefore clamped and held in proper relation to the last before the machine is started, thus relieving the operator of the necessity of holding the upper in the correct relation to the last by his hands until after the heel band and wipers begin to operate on the upper or, alternatively, relieving him of the necessity of driving tacks near the heel breast line to hold the upper in proper relation to the last before presenting the shoe to the machine. It will be understood that in the operation of the machine on a shoe of this type the pads 31, which are forced more firmly against the shoe through the spring 55 after the starting of the machine, serve further, as hereinbefore described, to prevent undesirable wrinkling of the upper immediately in front of its heel-end portion by the action of the heel band and wipers

on the shoe. Another advantage arising from the clamping of the upper by the pads 31 and the members 35 prior to the starting of the machine is that these pads and members when so positioned will thereafter have a forward pulling effect on the upper to draw it tightly about the heel end of the last when the jack is operated by power, as described in the above-mentioned Letters Patent No. 1,949,539, to carry the last and shoe farther rearwardly within the heel band after the starting of the machine.

The operation of the means provided by the invention will be clearly understood from the foregoing description. As the shoe-engaging pads 31 are forced firmly against the upper in the power operation of the machine, the yielding rubber of which they are made expands somewhat in directions both lengthwise and heightwise of the shoe, so that the pads press the upper in locations forwardly of the heel-breast line firmly against the sides of the last and against the edges of the insole or other shoe bottom part over substantial areas extending well below the level of the bottom face of the last. As the pads expand heightwise their upper edges rise far enough to press the upper against substantially the whole width of the edge of the insole so that the pads prevent any relative movement between this portion of the upper and the insole and accordingly prevent the formation of any objectionable wrinkles below the upper face of the insole as the wipers operate on the heel end of the upper. The pads 31 and the members 35, moreover, assist in holding the shoe and last firmly during the operation of the heel band and the wipers. It will be understood that after the wipers have completed their inward wiping movements the margin of the upper around the heel end is fastened in lasted position by a plurality of tacks driven as usual in machines of the illustrated type. Thereafter the wipers are retracted and the heel band is opened to release the shoe, the bell-crank levers 11 also being swung reversely to carry the members 31 and 35 away from the shoe. The jack then swings forwardly to its initial position to permit the removal of the shoe.

Having described the invention, what we claim as new and desire to secure by Letters Patent of the United States is:

1. In a lasting machine, the combination with heel-end-lasting mechanism comprising means for clamping an upper about the heel end of a last and wipers for wiping the marginal portion of the heel end of the upper inwardly over the bottom of the last, and a work support movable to present a last and shoe materials to said lasting mechanism, of upper-controlling means mounted independently of said work support and arranged to clamp the upper against the sides of the last in locations substantially at the edge of the shoe bottom forwardly of but near the heel-end portion of the shoe after the work support has received its work-presenting movement but prior to any substantial clamping action of said heel-end clamping means on the opposite sides of the heel end of the upper, the portions of said upper-controlling means adjacent to the shoe being located wholly at the same side of the plane of the wiping faces of the wipers as the shoe.

2. In a lasting machine, the combination with heel-end-lasting mechanism comprising a heel band for clamping an upper about the heel end of a last and wipers for wiping the marginal portion of the heel end of the upper inwardly over the bottom of the last, and a work support mov-

- able to present a last and shoe materials to said lasting mechanism, of members mounted independently of said work support and movable into positions to clamp the upper against the sides of
- 5 the last and against the edge of a shoe bottom part on the last in locations substantially adjacent to the forward ends of said heel band after the work support has received its work-presenting movement but prior to the closing of the heel
- 10 band on the opposite sides of the heel end of the upper, said members being located wholly at the same side of the plane of the wiping faces of the wipers as the shoe.
3. In a lasting machine, the combination with
- 15 heel-end-lasting mechanism comprising means for clamping an upper about the heel end of a last and wipers for wiping the marginal portion of the heel end of the upper inwardly over the bottom of the last, of clamping devices arranged
- 20 to act respectively at the opposite sides of the shoe forwardly of but near the heel-end portion of the shoe and each comprising a member for clamping the upper in a location adjacent to the edge of the shoe bottom and another member for
- 25 clamping and holding the shoe and last in a location spaced a substantial distance heightwise of the shoe from the edge of the shoe bottom, said members being guided independently of each other for movements widthwise of the shoe, and
- 30 means connecting the two members of each of said clamping devices together for substantially equalizing their pressures on the shoe.
4. In a lasting machine, the combination with
- 35 heel-end-lasting mechanism comprising a heel band for clamping an upper about the heel end of a last, and a work support movable to present a last and shoe materials to said lasting mechanism, of clamping devices mounted independently of said work support and movable into clamping
- 40 relation to the shoe and last in locations substantially adjacent to the forward ends of said heel band at the opposite sides of the shoe respectively after the work support has received its work-presenting movement but prior to any substantial
- 45 clamping action of the heel band on the opposite sides of the heel end of the upper, each of said clamping devices comprising a member for clamping the upper in a location adjacent to the edge of the shoe bottom and another member for
- 50 clamping and holding the shoe and last in a location spaced a substantial distance heightwise of the shoe from the edge of the shoe bottom, said members being guided independently of each other for movements widthwise of the shoe, and
- 55 means connecting the two members of each of said clamping devices together for substantially equalizing their pressures on the shoe.
5. In a lasting machine, the combination with
- 60 heel-end-lasting mechanism comprising means for clamping an upper about the heel end of a last and wipers for wiping the marginal portion of the heel end of the upper inwardly over the bottom of the last, of clamping devices arranged to act respectively at the opposite sides of the shoe
- 65 forwardly of but near the heel-end portion of the shoe and each comprising members slidably mounted to move relatively to each other in directions toward and from the shoe and provided respectively with means for clamping the upper
- 70 in a location adjacent to the edge of the shoe bottom and means for clamping and holding the shoe and last in a location spaced a substantial distance heightwise of the shoe from the edge of the shoe bottom; and an equalizing lever connect-
- 75 ing the two members of each of said clamping

devices together for substantially equalizing their pressures on the shoe.

6. In a lasting machine, the combination with heel-end-lasting mechanism comprising means for clamping an upper about the heel end of a last and wipers for wiping the marginal portion of the heel end of the upper inwardly over the bottom of the last, of clamping devices arranged to act respectively at the opposite sides of the shoe forwardly of but near the heel-end portion of the shoe and each comprising a member for clamping the upper in a location adjacent to the edge of the shoe bottom and another member for

10 clamping and holding the shoe and last in a location spaced a substantial distance heightwise of the shoe from the edge of the shoe bottom, a support common to both members of each of said clamping devices for moving them toward the shoe and relatively to which each member is movable widthwise of the shoe, and means movable at the will of the operator into position to maintain the clamping and holding member of each of said devices inoperative while the other member is in clamping position.

7. In a lasting machine, the combination with

15 heel-end-lasting mechanism comprising means for clamping an upper about the heel end of a last and wipers for wiping the marginal portion of the heel end of the upper inwardly over the bottom of the last, of clamping devices arranged

20 to act respectively at the opposite sides of the shoe forwardly of but near the heel-end portion of the shoe and each comprising a member for clamping the upper in a location adjacent to the edge of the shoe bottom and another member for

25 clamping and holding the shoe and last in a location spaced a substantial distance heightwise of the shoe from the edge of the shoe bottom, said members being guided independently of each other for movements widthwise of the shoe, means connecting

30 the two members of each of said clamping devices together for substantially equalizing their pressures on the shoe, and means movable at the will of the operator into position to maintain the two members of each of said devices in such positions that said clamping and holding member is

35 inoperative while the other member is operative.

8. In a power-operated lasting machine, the combination with heel-end-lasting mechanism comprising means for clamping an upper about the heel end of a last, of members arranged to clamp the upper to the sides of the last in locations forwardly of but near the heel-end portion of the last independently of said heel-end clamping means, means movable by the operator to force said members against the shoe prior to the starting of the power operation of the machine, and power-operated means for forcing said members more firmly against the shoe after the starting of the machine.

9. In a power-operated lasting machine, the combination with heel-end-lasting mechanism comprising means for clamping an upper about the heel end of a last, of members arranged to clamp the upper to the sides of the last in locations forwardly of but near the heel-end portion of the last independently of said heel-end clamping means, power-operated means including a lever movable to press said members firmly against the shoe after the starting of the power operation of the machine, and a device movable by the operator and arranged to act through said lever to move said members into upper-clamping positions prior to the starting of the machine.

10. In a power-operated lasting machine, the

combination with heel-end-lasting mechanism comprising a heel band for clamping an upper about the heel end of a last and wipers for wiping the marginal portion of the heel end of the upper inwardly over the bottom of the last, and a work support movable to present a last and shoe materials to said lasting mechanism, of members mounted independently of said work support and movable into positions to clamp the upper against the sides of the last in locations substantially adjacent to the forward ends of said heel band, means movable by the operator prior to the starting of the power operation of the machine to force said members against the shoe after the work support has received its work-presenting movement but prior to the closing of the heel band on the opposite sides of the heel end of the upper, and power-operated means for forcing said members more firmly against the shoe after the starting of the machine.

11. In a power-operated lasting machine, the combination with heel-end-lasting mechanism comprising means for clamping an upper about the heel end of a last and wipers for wiping the marginal portion of the heel end of the upper inwardly over the bottom of the last, and a work support movable in a direction lengthwise of a last thereon to present the work to said lasting mechanism prior to the starting of the power operation of the machine and further movable in the same direction after the starting of the machine, of members mounted independently of said work support for clamping the upper to the opposite sides of the last in locations near the forward end of the heel portion of the last, and

means movable by the operator to force said members against the upper after the work support has received its work-presenting movement but prior to the starting of the power operation of the machine to cause them to act with a forward tightening effect on the upper about the heel end of the last in response to the further movement of the work support after the starting of the machine.

12. In a power-operated lasting machine, the combination with heel-end-lasting mechanism comprising means for clamping an upper about the heel end of a last and wipers for wiping the marginal portion of the heel end of the upper inwardly over the bottom of the last, and a work support movable in a direction lengthwise of a last thereon to prevent the work to said lasting mechanism prior to the starting of the power operation of the machine and further movable in the same direction after the starting of the machine, of members mounted independently of said work support for clamping the upper to the opposite sides of the last in locations near the forward end of the heel portion of the last, means for moving said members into upper-clamping positions prior to the starting of the power operation of the machine to render them effective to tighten the upper forwardly about the heel end of the last in response to movement of the work support, and power-operated means for forcing said members more firmly against the upper after the starting of the machine.
